UNITED STATES PATENT OFFICE.

LOUIS F. SCHILLING, OF SALEM, OHIO.

COLLAPSIBLE BED.

1,354,343.

Specification of Letters Patent. Patented Sept. 28, 1920.

Application filed February 5, 1916. Serial No. 76,402.

To all whom it may concern:

Be it known that I, LOUIS F. SCHILLING, a citizen of the United States, residing at Salem, in the county of Columbiana and State of Ohio, have invented new and useful Improvements in Collapsible Beds, of which the following is a specification.

This invention relates to an improvement in collapsible beds. The invention, while having many features which render it generally useful and advantageous as an element of a touring or camping equipment, is directed more particularly to the problem of providing satisfactory sleeping accommodations for the automobilist during a tour, and it proposes a collapsible bed structure which is especially adapted for combination with an automobile as a part of the touring equipment.

The objects of the invention, briefly stated, are to provide a collapsible bed for use on tour which may be combined with any type or construction of automobile; which may be set up at one side externally of the car, enabling the convenient use of the tonneau for disrobing and for the storage of clothes and luggage; which, when set up, may be arranged in such relation to the tonneau that one, upon disrobing in the tonneau, may step through the door of the car directly into the bed, and which in this relation to the tonneau may be completely closed in by a canopy or shelter top providing a sleeping compartment as a direct lateral continuation of the tonneau in order that one may step from the tonneau into the bed, without exposure; which, while providing for a closed-in or sheltered sleeping space or compartment, at the same time admits of the free circulation of fresh air through the sleeping space or compartment; which will be substantially as comfortable and easy as an ordinary domestic bed; which, regardless of the environment of use, may be collapsed into exceedingly small compass, so small, in fact, that when provided as a part of an automobile touring equipment and not in use, it may be conveniently carried on the running board, thereby being entirely out of the way of the occupants of the tonneau and rendering it unnecessary to provide any special bed carrier of unsightly or bulky character; which may be quickly and readily set up and as quickly and readily collapsed and disposed on the running board or other

support; and which will be strong, inexpensive and durable, and in no way liable to derangement.

An embodiment of the invention is illustrated in the accompanying drawings, wherein:

Fig. 1 is a view showing a cross section of the automobile body and the improved bed set up at one side thereof;

Fig. 2 is a view showing the bed set up, in end elevation, with the automobile in side elevation;

Fig. 3 is a plan view of the bed, the canopy or shelter top being removed;

Fig. 4 is an end elevation of the bed with the canopy or shelter top removed;

Figs. 5, 6, 7, 8 and 9 are side elevations showing various relations of the parts of the bed in the course of the operation of collapsing it and disposing it upon the running board or other support;

Fig. 10 is a plan view of the bed with its parts in the relations in which they are shown in Fig. 8;

Fig. 11 is an elevation showing the bed with its parts in the relations in which they are shown in Fig. 9;

Fig. 12 is a detail perspective view showing the relation between the supporting legs of the bed and the elements of a transverse bracing means for said legs;

Fig. 13 is a detail perspective view showing the relation between the side and end bars;

Fig. 14 is a detail perspective view showing the relation between the side and end bars of a collapsible supporting bow for the canopy or shelter top;

Figs. 15 and 16 are detail plan and sectional views showing the corner construction of the supporting bow for the canopy or shelter top with a side bar of said bow in extended and folded relation;

Fig. 17 is a detail sectional view showing the relation between the side bars of the bed and the swiveling sleeve by which said bars are connected to the running board or other support;

Fig. 18 is a detail perspective view of the swiveling sleeve shown in Fig. 17;

Fig. 19 is a detail perspective view of the post about which the sleeve swivels;

Fig. 20 is a detail perspective view of a clip by which each side bar of the bed is connected to the swiveling sleeve shown in Fig. 19;

Fig. 21 is a detail fragmentary side elevation, partly in section, showing the relation between the side bars of the bed frame and the braces which support them from the legs;

Fig. 22 is a view similar to Fig. 21 but looking at the inner sides of said side bars;

Fig. 23 is a detail cross sectional view on the line 23—23 of Fig. 22; and

10 Figs. 24 and 25 are detail views showing the connections between the canopy or shelter and the roof of the tonneau.

Similar characters of reference designate corresponding parts throughout the several 15 views.

The improved bed, as previously stated, is specially adapted for operative combination with an automobile, and it is shown in the drawings in its preferred relation, *i. e.*, so 20 arranged that it may, when set up, be extended laterally at one side of the tonneau and when collapsed may be disposed along the running board, as shown more particularly in Figs. 9 and 11.

25 The automobile A, with its running board *a*, may be of any desired construction. The bed is associated with the running board *a*, and its frame consists of two side bars 1 and an end bar 2. Each side bar 1 consists 30 of two sections 1^a and 1^b pivotally connected whereby the outer section 1^b may be swung in a vertical plane into parallel relation with the inner section 1^a, as shown more particularly in Fig. 6. The end bar 2 connects the sections 1^b.

When the bed is set up, the end bar 2 is parallel to the running board *a*, as shown more particularly in Fig. 3; and said end bar and running board conjointly support 40 the bed spring fabric 3, which is suspended by transverse series of extension springs 4 in the same way that a bed spring fabric is ordinarily suspended between the end bars of a bed frame of usual construction.

45 The bed spring fabric 3, in consideration of the adaptability of the bed to the needs of automobilists on tour, should be of a construction whereby it may be folded or rolled into exceedingly small compass. It is preferably of the construction shown in my co-pending application for patent upon bed spring fabrics, Serial No. 68533, which is the best construction of which I am aware for the purpose in view, in that it may be 50 rolled into the form of a tube whose diameter is substantially less than the width of the running board, as clearly shown in Fig. 9.

When the bed is set up, it is supported at 55 a fixed and sanitary elevation above the ground, at one end thereof by the running board or equivalent support *a*, which functionally constitutes an end bar of the bed frame, and at or near its other end by legs 5 which are pivotally secured to the side

bars 1, preferably by the same pivot pin which connects the sections 1^a and 1^b of said side bars. The legs 5 not only participate in supporting the bed as an entirety at a fixed elevation above the ground but they 70 are, preferably, utilized in holding the sections 1 and 1^b in alining relation, as shown in Fig. 1. For this purpose, each leg 5 is connected with the respective sections 1^a and 1^b of its companion side bar by diagonal 75 braces 6^a and 6^b which, at their lower ends, are pivoted to the leg 5 and, at their upper ends, are detachably connected to the side bar sections 1^a and 1^b in any suitable manner, for example, by headed pins 6^c engaging 80 through openings 6^d in said side bar sections, the upper walls of said openings resting upon the shanks of said pins and being held between their heads and the braces 6^a and 6^b.

In collapsing the bed and storing it on the running board, the end bar 2 is disconnected from the side bars 1. The side and end bars are preferably of angle iron construction, and to provide for their ready connection and disconnection the side bar sections 1^b are provided at their extremities and adjacent their corners in their vertical webs with slots 7 in which the extremities of the flat web of the end bar 2 are engaged, as will be clearly apparent from Fig. 13. The flat web of the end bar 2 is preferably provided at its ends with slots 8 which take over the vertical webs of the side bar sections 1^b. In this way, the extremities of the side bar sections 1^b and of the end bar 2 are securely associated by a tongue-and-slot connection of certain of their parts which enables the end bar 2 to be fitted to or separated from the side bar sections 1^b by a movement toward and from said side bar sections and the end bar 2 preferably has at its ends overhanging flanges 2^a which fit over the side webs of the side bar sections 1^b.

To permit of the storage of the bed along the running board, as shown by Figs. 9 and 11, the side bar sections 1^a are connected at their inner ends whereby the side bars may be swung into parallel relation and in such relation supported on the running board. These connections comprise a clip 9 secured to the front end of each side bar section 1^a, sleeves 10 to which the clips 9 are pivoted for vertical movement and vertical posts 10^a 115 upstanding from the running board and about which the sleeves 10 may swivel, said posts having retaining nuts or cotter pins on their upper ends. The pivotal connection of the clips 9 to the sleeves 10 enables the elevation of the bed to be adapted to the surface of the ground which is engaged by the legs 5.

The legs 5, as above explained, are braced to the side bar sections 1^a and 1^b by the 120

85

125

parts 6^a and 6^b. The said legs are also braced to one another, the means employed consisting of a rigid brace bar 11 provided with pivoted supplemental brace members 12. The brace bar 11 extends between the legs 5 and is preferably made in sections 11^a, each of which is pivoted to one of the brace members 12 and is provided with headed terminal projections 11^b. The projections 11^b engage in slots 13 formed longitudinally in lateral projections 5^a on the legs 5, the latter for this purpose being preferably of angle iron form, as shown more particularly in Fig. 12. The brace members 12 are pivoted to the projections 5^a at fixed points above the slots 13. The brace sections 11^a at their inner ends are each provided with pins 11^c for engagement through an opening 11^d in the other; and the overlying portions of the sections 11^a are held in connected or engaged relation by a clip 11^e which has a U-shaped cross section and may be removed from the parts 11^a, to permit of the disengagement of their overlying ends in connection with the collapse of the bed whereby each section 11^a and the member 12 connected thereto may be folded under the adjacent side bar section 1^a.

30 An important advantage of the arrangement of the bed at the side of the tonneau as shown is that a canopy or shelter top may be placed over the bed to provide a sleeping compartment which forms, in effect, a lateral continuation of the tonneau, enabling the user of the bed to disrobe in the tonneau, and upon disrobing to step, without exposure, directly into the bed, the tonneau being used for the over-night storage of the clothing. The canopy or shelter top 15 is made of any suitable material, such as canvas or waterproof fabric, and as shown in Fig. 25, is formed, adjacent its inner edge, with a transverse pocket 16 inclosing a bar Y which is suspended by tapes 16^a from the bow framing of the roof. The canopy is provided with a flap 16^b which extends beyond the pocket 16 and may be fitted between the bows and top fabric of the roof and which renders it unnecessary to cut the canopy for the purpose of fitting it to the roof of the tonneau. The canopy is cut away near its outer end and at each side thereof in order that its outer portion may form a depending wall 17 transverse to the bed which closes the rear end of the sleeping compartment, the sides of the cut-away portions of the canopy being secured together at each side of the bed by buttons or equivalent fastenings 18.

35 The canopy or shelter top is supported, in part by the roof of the tonneau and in part by a bow 19 from which the wall 17 depends. This bow is preferably connected to the bed frame for support thereby, its trans-

verse member 19^a being fitted in a sleeve 20 associated with the canopy, as shown in Fig. 14, while its side members 19^b are hingedly secured to the member 19^a and are pivotally and detachably secured to the side bar sections 1^b. The bow 19 is subjected to a constant downward pull, in order that the roof portion of the canopy top may be maintained substantially taut, notwithstanding wind pressure or the weight of any rain 75 water or snow that may accumulate thereon during the night. For this purpose, it is preferred to provide retractile coil springs 21 between the bars 19^b of the bow 19 and the side bar sections 1^b.

40 The members 19^a and 19^b of the bow 19 are preferably made of wood and are hingedly connected in the manner shown in Figs. 14-16. Thus the member 19^a is provided at each end with an angle fitting 19^c having 85 inwardly projecting parallel plates 19^d which provide a socket for the upper end of the adjacent member 19^b. The portion of the member 19^b which fits between the plates 19^d has a longitudinal slot 19^e through 90 which passes a pivot pin 19^f that connects or extends between the plates 19^d. The said plates have at their outer edges inturned relatively short flanges 19^g which, in the use of the bow, prevent the upper or outer ends 95 of the members 19^b from swinging laterally outward from the sockets provided therefor by the plates 19^d but which enable said members, after they have been withdrawn from their sockets as far as permitted by the pins 19^f to be swung inwardly into parallel relation to the member 19^a, as shown in Fig. 16 to facilitate the rolling up or folding of the canopy for storage. The members 19^b may have at their lower ends headed pins 105 fitting in openings in the side bar sections 1^b, similarly to the pins 6^c of the braces 6^a-6^b to provide for the above-mentioned detachable and pivotal connection of the bow and the side bars 1. The canopy or 110 shelter top preferably terminates above the ground in order to provide for the free circulation of air through the sleeping compartment.

45 When the bed is collapsed and stored on the running board, the side bars 1, with their sections 1^a and 1^b in folded relation, extend parallel to one another and are disposed under the inner marginal portion of the bed spring fabric, as shown in Fig. 9, 115 120 the said fabric thus providing a shelter for the said bars of the bed frame, its marginal portion which overlies said side bars being inclined downward and thereby shedding water. The bed spring fabric is arranged 125 in a relatively compact tubular roll which is supported on the running board, being disposed longitudinally thereof between the wall of the tonneau and the folded side bars of the bed frame and which, as shown in 130

Fig. 9, is utilized to inclose the end bar 2. If desired, the canopy or shelter top with the bow 19 folded therewith and parts of the bedding may be fitted, along with the end bar 2, within the hollow center of the roll, into which the bed spring fabric is formed.

In order to set up the bed, the side bars 1 are turned to project outwardly at right angles from the running board *a*, and their 10 sections are extended, the sections 1^a being connected to the braces 6^a which insure the rigidity of the legs 5. The bed spring fabric is then unrolled, and upon the completion of this unrolling the end bar 2 is engaged with the side bar sections 1^b in the manner clearly indicated by Fig. 13 and shown more in detail in Fig. 3. To promote the fitting of the end bar 2 to the sections 1^b, the latter should be held at the 20 angle shown by full lines in Fig. 5 in order that there may be no tension on the springs 4. After the end bar 2 has been fitted to the sections 1^b, said sections are extended into alining relation to the sections 1^a and 25 connected to the braces 6^a. The springs 4 will then be under tension and hence will hold the end bar 2 securely in position. When the bed spring fabric has been unrolled, the parts fitted in the center of the 30 roll and dissociable from the fabric, if any there be, are removed. Thereupon the brace comprising the bar 11 and the members 12 is arranged between the legs 5 in the manner described and, as shown in Fig. 12, the terminals of its sections 11^a are engaged in overlying relation and held together by the 35 clip 11^b. The bow 19 combined with the canopy or shelter top is then arranged in operative relation, its side bars 19^b being 40 extended at right angles to the transverse bar 19^a with their upper ends securely fitted in the sockets provided by the plates 19^d and their lower ends connected to the side bar sections 1^b. The canopy or shelter top is 45 then connected to the bar Y adjacent the inner face of the side of the roof or cover of the tonneau, as above described, and shown in Fig. 1, after which the springs 21 are connected to the parts 19^b of the bow and 50 to the side bar sections 1^b and the cut-away portions of the canopy are connected by the fastenings 18.

To collapse the bed and dispose it for storage upon the running board *a*, the operations are performed in the reverse order to that described and will, therefore, be obvious.

It is to be noted that the end bar 2 need not be detached from the bed spring fabric 3 in connection with the extension or collapse of the bed. Thus, the said end bar will be disposed in the center of the tube into which the mattress is ultimately rolled, as an incident of the mattress-rolling opera-

tion. The tubular center of the roll in which 65 the mattress is formed is, or may be, made amply sufficient for the reception of the incidental parts of the structure, including the canopy and the bedding or parts thereof, notwithstanding that the mattress is rolled 70 into sufficiently small compass to occupy only a portion of the width of the running board.

In the operation of collapsing the bed, the legs 5 are folded at the lower sides of the 75 side bar sections 1^a and the side bar sections 1^b are folded at the upper sides of the sections 1^a, the latter and the legs 5 having a nested relation and the braces 6 extending in parallel relation to the sections 1^a at the 80 sides thereof.

After the legs 5 have been folded, the brace sections 11^a are disconnected and each brace section, together with its companion member 12, is folded under the leg 5 with 85 which it is associated in parallel relation to the adjacent side bar section 1^a.

It will be observed that when the bed is collapsed and disposed for storage on the running board in the manner described, the 90 bed spring fabric, which is preferably composed of canvas, as described in my co-pending application, affords a thorough and serviceable protection for the metallic parts of the structure, directly inclosing the end 95 bar 2, and providing a water-shedding covering for the side bars 1 and the parts associated therewith.

While in the construction of the bed as above described the running board could be 100 utilized as an end bar of the bed frame, and in any event, in its function of supporting the inner end of the bed frame and the bed spring fabric, discharges the function of an ordinary bed frame end bar, it is preferred, 105 in order that the structure may be of unitary character, to secure the springs 4 at the inner end of the bed spring fabric to a plate 22 which also carries the posts 10^a about which the side bars are swung horizontally in the collapse or extension of the bed, as above explained. The plate 22 is co-extensive with and parallel to the end bar 2 and is imposed on the running board *a*, 110 being held in position thereon by bolts or equivalent devices. By virtue of the provision of the plate 22, the bed structure, including the bed frame, the bow 19, the brace between the legs 5, and the bed spring fabric, may be removed or replaced as a 115 unit relatively to the running board *a*. By virtue of the unitary character of the bed, the entire bed structure may be rolled within the bed spring fabric 3, when it is desired, as for the adaptation of the car to ordinary city use, to remove the bed from the 120 running board and to place it in stationary storage.

125

In some automobiles the rear fender is set forward to such extent, as shown by the dotted lines X in Fig. 2, that the length of the running board between the rear fender 5 and the front of the tonneau is less than the width of the canopy or shelter top. The running board will, in any event, however, have a maximum length at least equal to the width of the canopy or shelter top; 10 and in such cases, to compensate for the advanced position of the runner X, the bar Y will be arranged to project forwardly to a suitable extent beyond the front of the roof of the tonneau, the front portion of 15 the canopy or shelter top being turned back toward the wind shield with its upper edge secured in any suitable manner to the projecting portion of the bar Y.

It will be understood that no specific description herein contained is intended to put any limitation upon the scope of the appended claims, which does not inhere in the language thereof.

Having fully described my invention, I 25 claim:

1. In a collapsible bed, a frame comprising a horizontal end bar constituting a support, side bars, each having a swiveling connection at its inner end with said support, 30 said side bars being thereby foldable through an angle of ninety degrees whereby they may be projected in parallel relation to one another and at a right angle to said support or may be disposed to rest on said support in parallel relation to one another, and a second end bar connecting the outer ends of said side bars, and being detachable therefrom prior to the folding of said side bars, said second end bar, when assembled, 35 being parallel to said support.
2. In a collapsible bed, a frame comprising a horizontal end bar constituting a support, side bars, each having a swiveling connection at its inner end with said support, 45 said side bars being thereby foldable through an angle of ninety degrees whereby they may be projected in parallel relation to one another and at a right angle to said support or may be disposed to rest on said support in parallel relation to one another, and each comprising a pair of foldably related sections and means for maintaining said sections in rigid alignment, and a second end bar connecting the outer ends of 50 said side bars and being detachable therefrom prior to the folding of said side bars, said second end bar, when assembled, being parallel to said support.
3. In a collapsible bed, a frame comprising an end support, side bars, a pair of members mounted on said support for swiveling movement, each side bar having a horizontal pivotal connection with one of 55 said members, a leg foldably related to each side bar, and an end bar connecting the 60 outer ends of said side bars and being detachable therefrom, said end bar, when assembled, being parallel to said support.
4. In a collapsible bed, a frame comprising an end support, side bars, each having a swiveling connection at its inner end with said support, a leg foldably related to each side bar, brace means extending between the legs and including elements associated with the respective legs and constructed for detachable connection with one another, and an end bar connecting the outer ends of 65 said side bars and being detachable therefrom, said end bar, when assembled, being parallel to said support.
5. In a collapsible bed, a frame comprising an end support, side bars, each having a swiveling connection at its inner end with said support, a leg foldably related to each side bar and having a lateral extension provided with a longitudinal slot, brace means 70 extending between the legs comprising a transverse bar made in sections constructed for detachable connection with one another and each having an end projection pivotally and slidably engaging in the slot of the adjacent leg and brace members pivoted to the legs above said slots and also pivoted to the respective sections of said transverse bar, and an end bar connecting the outer ends of 75 said side bars and being detachable therefrom, said end bar, when assembled, being parallel to said support.
6. In a collapsible bed, a frame comprising an end support, side bars, each having a swiveling connection at its inner end with said support, means extending transversely of the bed for bracing the side bars to one another having detachably connected elements and including bed supporting legs 80 foldably related to said side bars, and an end bar connecting the outer ends of said side bars and being detachable therefrom, said end bar, when assembled, being parallel to said support.
7. In a collapsible bed, a frame comprising an end support, side bars, each having a swiveling connection at its inner end with said support and each comprising a pair of foldably related sections, a supporting leg 85 pivotally connected to each side bar, braces between each leg and the two sections of its companion side bar, said braces being detachably connected to said side bar sections, and an end bar connecting the outer ends of 90 said side bars and being detachable therefrom, said end bar, when assembled, being parallel to said support.
8. In a collapsible bed, a frame comprising an end support, side bars, each having a swiveling connection at its inner end with said support and each comprising a pair of foldably related sections, a supporting leg 95

extension of the common plane in which the said outer end portions of the side bars are disposed.

15. The combination of an automobile body, a collapsible bed projecting laterally from the running board thereof, a flexible canopy or shelter top extending over the bed to provide a sleeping compartment closed at its sides and outer end, means supporting the inner end of the canopy or shelter top adjacent the automobile body, a bow carried by the canopy top and detachably and pivotally connected to the bed for supporting the canopy or shelter top at its outer end, and springs to urge the bow toward the bed.

16. In a collapsible bed, a frame comprising a horizontal end member, consisting of a support, side bars, each having a movable connection at its inner end with said support, said side bars being by reason of their movable connection with the support, foldable through an angle of 90 degrees, to project them in parallel relation to one another and at a right angle to said support, or to be disposed to rest on said support in parallel relation to one another, and an end bar detachably connected with the outer ends of said side bars.

17. An automobile bed having side members composed of sections pivoted together intermediate the extremities of said side members and adapted to be collapsed longitudinal of each other, an end support upon which corresponding sections of said side members are fulcrumed to swing in a lateral direction, an end bar adapted for detachable connection to the other sections of said side members at the free ends thereof, and a flexible bed spring fabric supported by and between said end bar and said support, said fabric carrying said end bar and being in turn carried by said support.

18. In a collapsible bed, a frame comprising an end support, side bars, a pair of members mounted on said support for swiveling movement, each side bar having a horizontal pivotal connection with one of said members and also having ground-engaging supporting means intermediate its extremities, and an end bar connecting the outer ends of said side bars and being detachable therefrom, said end bar, when assembled, being parallel to said support.

19. In a collapsible bed, a frame comprising a horizontal end member, side bars each

comprising an inner section having a movable connection at its inner end with said end member and being by reason of its movable connection with said end member foldable through an angle of 90 degrees to lie in parallel relation with said end member, and an outer section, said outer sections each having a horizontal pivotal connection with one of said inner sections so as to fold upon the latter, each side bar having ground-engaging supporting means intermediate its extremities, and an end bar connecting the outer ends of said outer sections, said end bar, when connected to the ends of said outer sections, being parallel to said horizontal end member.

20. A collapsible bed having a relatively stationary head end member, side bars adapted to be projected from said head end member in parallel relation to one another, side bars each including inner sections movably connected to said head end member to provide for the collapse of the bed, and outer sections pivotally connected to said inner sections for movement in vertical planes, said outer sections being thereby adapted to be folded upon said inner sections and to be extended relatively to said inner sections, an end bar connecting the free ends of the outer sections, said end bar being detachable from said outer sections, and a flexible bed spring fabric supported free of said side bars by and between said end bar and said head end member, said fabric carrying said end bar and being in turn carried by said head end member, said outer sections serving, when fully extended, to locate said end bar in a substantially horizontal plane common to said end bar, said inner sections and said head end member and also serving, in connection with the extension of said outer sections, to take up all slack in said fabric, whereby when said sections are fully extended, said fabric will lie flat and will be substantially located in said common horizontal plane.

In testimony whereof I have hereunto set my hand in presence of two subscribing witnesses.

LOUIS F. SCHILLING.
